SEAL

William Artzt, New Rochelle, and Mark Rubinoff,
New York, N. Y., assignors to Sealtag, Inc.,
New York, N. Y., a corporation of New York

Application March 17, 1944, Serial No. 526,979

6 Claims. (Cl. 292—307)

1

This invention relates to improvements in seals and is particularly directed to seals for preventing the unauthorized separation of two or more articles.

More specifically the invention is directed to the type of seals generally employed in the sale of garments, where it is desired to prevent a purchaser from taking a garment home, wearing the same in public and then returning the worn garment to the vendor. In such use a seal, or a sealed tag is attached in a prominent place on the garment and cannot be removed without mutilation.

One of the objects of the present invention resides in the provision of a seal which is inexpensive to manufacture and which can readily be attached to a garment or other article.

Another object of the invention is the provision of a string, wire or other filament one end of which is permanently secured to the seal and the other end provided with a needle for facilitating the application thereof to a garment.

A further object of the present invention is the provision of a seal adapted to receive the needle carried on the free end of the string, after the same has been passed through a garment or other article, whereby the ends of the loop formed by the string will be securely locked in the seal in such a manner that the seal can not be removed without mutilating the seal or the string.

Other objects of the present invention will be manifest from the following description and the accompanying drawing, in which drawing:

Fig. 1 is a sectional elevational view of our improved seal;

Fig. 2 is an enlarged sectional view taken on line 2—2 of Fig. 1;

Fig. 3 is a cross sectional view taken on line 3—3 of Fig. 1;

Fig. 4 is a plan view, on a reduced scale, of a blank from which the seal is made;

Fig. 5 is a fragmentary view of one end of a modified form of seal;

Fig. 6 is a side view thereof;

Fig. 7 is a sectional elevational view of a further modified form of seal; and

Fig. 8 is a sectional view taken on line 8—8 of Fig. 7.

Referring to the drawing in detail and first of all to the embodiment illustrated in Figs. 1 to 4 inclusive, a blank 10, as shown in Fig. 4 may be stamped out of metal and provided with opposed cut out portions 12 and 14 and end tabs or projections 16 and 18.

For convenience of description the portion of

2

the blank designated 20 will be referred to as the front wall and the portion designated 22 as the rear wall. The front wall is provided with side flanges 24 and 26 and the rear wall is provided with side flanges 28 and 30. These flanges are bent inwardly at right angles to the planes of their respective walls and the walls are folded upon themselves along the dot and dash lines 32 and 34 respectively to provide an end wall 36. This end wall is provided with a central aperture 38, having a flange 40, as more clearly shown in Figs. 1 and 2.

The tab 18 on the rear wall has an aperture designated 42 formed therein, the purpose of which will be described presently. The tab 16 of the front wall has an aperture 46 provided with a flange 44 and a circular groove or depression 48 surrounding the aperture and provided with a radial groove extending to the end of the tab. When the walls are folded over upon each other as hereinbefore mentioned the flanges of each wall overlap the flanges of the other as shown in Fig. 2, and the flange 44 in the tab 16 of the front wall passes through the aperture 42 in the tab 18 of the rear wall as shown in Fig. 2. One end of a string 50 is placed in the groove 48 as shown in Fig. 1 and the flange 44 is clinched over the rear wall as shown in Fig. 2 whereby the string is securely held between the tabs 16 and 18.

The other end of the string 50 is provided with a needle 52. As will be seen from Fig. 1 the needle comprises a pointed portion 56 and a tubular portion 54 in which the end of the string is securely held by crimping the same thereover.

When it is desired to attach the seal to a garment or other article 58 the needle is passed through the article and then inserted into the seal through the orifice 38 which is only of sufficient diameter to permit the needle and string to pass therethrough. Once the needle has thus been inserted in the seal it will be appreciated that it will be impossible to remove the same therefrom. Should an attempt be made to remove the needle by pulling on the string, the needle will move to the dotted line position, shown in Fig. 1, and will be restrained against removal by the flange 40 as well as by the restricted size of the orifice 38.

If it is desired to attach a tag, in addition to the seal, to the garment or article, the needle either before or after it is passed through the garment may be passed through a tag (not shown).

As will be appreciated the crimping or riveting

of the flange 44 over the rear wall will prevent the seal from being opened to remove either the anchored end or the end carrying the needle, thereby making it impossible to remove the seal or the tag (if one is attached) from the garment without mutilation of the seal, string or garment.

In the embodiment illustrated in Figs. 5 and 6 the string is anchored to the seal in a different manner than illustrated in Figs. 1 and 2. In this form rear wall 60 is provided with a longitudinal groove 62 for receiving the end of the string 64. Tab 66 on the rear wall in this form is slightly longer than the tab 68 on the front wall. After the end of the string to be anchored is placed in the groove 62 the end of the tab 66 is folded over upon the tab 68 of the front wall to securely clamp the end of the string to the seal.

With respect to the embodiment illustrated in Figs. 7 and 8 the seal comprises front and rear walls 70 and 72 respectively each having side flanges 74 and 76 respectively overlapped when the seal is formed in the same manner as in the form illustrated in Figs. 1 to 4 inclusive. The top and bottom walls 78 and 80 are provided with orifices 82 and 84 respectively. The orifice 84 is adapted to receive the end of a string 86 to be anchored which is threaded therethrough before the walls are folded upon themselves and is provided with a knot 88 whereby to anchor the same in the seal.

The front and rear walls each have a flange 96 and 98 struck inwardly to provide spring members for the purpose to be described presently.

The free end of the string 86 carries a needle 94 similar to that shown in Fig. 1.

As will be seen from the drawing the flanges or spring members 96 and 98 normally have their inner edges about in vertical alignment with each other. As the needle is inserted through the orifice 82 it is forced past these members, which yield to permit passage of the needle, so that the needle, when completely inserted, is thrown to one side as shown in Fig. 7 whereby the same can not be removed from the seal.

It will be appreciated that the present invention provides an effective seal which is tamper-proof, economical and readily attached to a garment or other article.

The importance of having the front and rear walls securely and irremovably attached to each other will be appreciated since the separation of the walls would permit the removal of the string. However, while we have illustrated and described certain embodiments of securing means, it is to be understood that the present invention is not limited to such securing means as obviously the walls may be secured by welding, soldering, riveting or in many other ways within the scope of the present invention.

It is to be understood that while we have illustrated and described other structural embodiments of our invention we do not wish to be limited to these precise structures as obviously various changes and modifications may be made therein without departing from the spirit and scope of our invention.

What we claim is:

1. A seal comprising an elongated hollow body member comprising spaced front and rear members provided with overlapping flanges along their edges and an integral connection between one pair of ends of said members constituting

an end wall of said body member, said end wall being provided with a needle orifice, the other pair of ends of said members extending beyond the ends of said flanges and in overlapping engagement with each other, a filament having one of its ends lying between said overlapping ends, means securing said overlapping ends together and securing said end of said filament therebetween, a needle carried by the other end of said filament and adapted to be passed through said needle orifice into said body member, and means constituting a portion of said body member for preventing withdrawal of said needle from said body member.

15. 2. A seal comprising an elongated hollow body member comprising spaced front and rear members provided with overlapping flanges along their edges and an integral connection between one pair of ends of said members constituting

an end wall of said body member, said end wall being provided with a needle orifice, the other pair of ends of said members extending beyond the ends of said flanges and in overlapping engagement with each other, a filament having one of its ends lying between said overlapping ends, means securing said overlapping ends together and securing said end of said filament therebetween, a needle carried by the other end of said filament and adapted to be passed through said

20. 25. 30. 35. 40. 3. A seal comprising an elongated hollow body member comprising spaced front and rear members provided with overlapping flanges along their edges and an integral connection between one pair of ends of said members constituting

an end wall of said body member, said end wall being provided with a needle orifice, the other pair of ends of said members extending beyond the ends of said flanges and in overlapping engagement with each other, a filament having one of its ends lying between said overlapping ends, means securing said overlapping ends together and securing said end of said filament therebetween, a needle carried by the other end of said filament and adapted to be passed through said

25. 30. 35. 40. 3. A seal comprising an elongated hollow body member comprising spaced front and rear members provided with overlapping flanges along their edges and an integral connection between one pair of ends of said members constituting

an end wall of said body member, said end wall being provided with a needle orifice, the other pair of ends of said members extending beyond the ends of said flanges and in overlapping engagement with each other, a filament having one of its ends lying between said overlapping ends, means securing said overlapping ends together and securing said end of said filament therebetween, a needle carried by the other end of said filament and adapted to be passed through said

45. 50. 55. 60. 65. 70. 75. 3. A seal comprising an elongated hollow body member comprising spaced front and rear members provided with overlapping flanges along their edges and an integral connection between one pair of ends of said members constituting

an end wall of said body member, said end wall being provided with a needle orifice, the other pair of ends of said members extending beyond the ends of said flanges and in overlapping engagement with each other, a filament having one of its ends lying between said overlapping ends, means securing said overlapping ends together and securing said end of said filament therebetween, a needle carried by the other end of said filament and adapted to be passed through said

45. 50. 55. 60. 65. 70. 75. 3. A seal comprising an elongated hollow body member comprising spaced front and rear members provided with overlapping flanges along their edges and an integral connection between one pair of ends of said members constituting

an end wall of said body member, said end wall being provided with a needle orifice, the other pair of ends of said members extending beyond the ends of said flanges and in overlapping engagement with each other, a filament having one of its ends lying between said overlapping ends, means securing said overlapping ends together and securing said end of said filament therebetween, a needle carried by the other end of said filament and adapted to be passed through said

45. 50. 55. 60. 65. 70. 75. 3. A seal comprising an elongated hollow body member comprising spaced front and rear members provided with overlapping flanges along their edges and an integral connection between one pair of ends of said members constituting

an end wall of said body member, said end wall being provided with a needle orifice, the other pair of ends of said members extending beyond the ends of said flanges and in overlapping engagement with each other, a filament having one of its ends lying between said overlapping ends, means securing said overlapping ends together and securing said end of said filament therebetween, a needle carried by the other end of said filament and adapted to be passed through said

45. 50. 55. 60. 65. 70. 75. 3. A seal comprising an elongated hollow body member comprising spaced front and rear members provided with overlapping flanges along their edges and an integral connection between one pair of ends of said members constituting

an end wall of said body member, said end wall being provided with a needle orifice, the other pair of ends of said members extending beyond the ends of said flanges and in overlapping engagement with each other, a filament having one of its ends lying between said overlapping ends, means securing said overlapping ends together and securing said end of said filament therebetween, a needle carried by the other end of said filament and adapted to be passed through said

posite sides of said body member terminating substantially in alignment with each other and said orifice.

5. A seal comprising a hollow elongated body member having front and rear walls, tabs formed on said walls at one end thereof, cooperating means on said tabs for securing said walls to each other, side flanges on each of said walls to provide closed side walls, an end wall at the other end of said walls and having an aperture therein, a filament, a needle carried by one end of said filament and adapted to be inserted through said aperture and being constructed and arranged to be completely disposed in said body member, said front and rear wall securing means also anchoring the other end of said filament to said body member, and means for retaining said needle in said body member.

10 6. A seal comprising a hollow elongated body member having front and rear walls, a portion of one of said walls being folded over upon and secured to a portion of the other of said walls, said portions being at one end of said body member, side flanges on each of said walls overlapping each other to provide closed sides, an end wall at the other end of said body member having an aperture therein, a filament, a needle carried by one end of said filament and adapted to pass

through said aperture and constructed and arranged to be disposed completely in said body member, the other end of said filament being secured to said body member between said portions of said first mentioned walls, and means formed in said body member for retaining said needle in said body member.
